FRANCESCO MARTUCCI, OF JERSEY CITY, NEW JERSEY.

SANITARY SOAP-HOLDER.

1,328,177.

Specification of Letters Patent. Patented Jan. 13, 1920.

Application filed June 17, 1919. Serial No. 304,867.

To all whom it may concern:

Be it known that I, FRANCESCO MARTUCCI, a citizen of the United States, and a resident of Jersey City, in the county of Hudson and State of New Jersey, have invented 5 a new and Improved Sanitary Soap-Holder, of which the following is a full, clear, and exact description.

This invention relates to barbers' supplies 10 and has particular reference to soap holders or shaving mugs.

Among the objects of the invention is to provide an attachment for a shaving mug or the like adapted to hold a cake or mass of 15 soap in elevated position, but so designed as to make it convenient and easy for the operator to depress the mass of soap so as to plunge it more or less beneath the surface of a small body of water retained normally be- 20 low the mass of soap.

Another object of the invention is to provide a soap holder with means for automatically supporting it above the surface of the body of water to which the holder is connected for two immediate purposes: first, to economize in the amount of soap used by keeping it out of direct contact with the water, and secondly to cause the soap holder to act as a brush support whereby the shaving man may keep the brush within the receptacle so as to prevent the drip from the brush from soiling the washstand or table during the brief periods of inactivity of the brush, and yet provide a means whereby the 35 brush is not retained during those periods it is plunged into the water in the receptacle.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a vertical sectional view of a shaving mug or the like and indicating my 50 improved soap holder mainly in side elevation therein.

Fig. 2 is a perspective view of the holder detached; and

Fig. 3 is a horizontal section on the line 3—3 of Fig. 2, showing the tray portion of 55 the soap holder in plan view.

Referring now more specifically to the drawings the receptacle 10 may obviously be of any suitable size, construction or design and ordinarily is provided with a handle 11 60 for manipulation thereof. Within the receptacle is a supply of water 12 extending somewhat above the body.

My improved soap holder comprises a tray 13 shown as having a flat bottom 14 with 65 any suitable number or size of holes 15 for the free passage of water through the bottom in both directions. The tray includes also an upstanding flange 16.

17 indicates a bracket having at its upper 70 end a hook 18 adapted to engage over the rim of the mug preferably just above the handle 11. The bracket is formed preferably of sheet or strap metal and adjacent to the point of the hook there is provided a 75 flat section 19 from which there extends upward a stud or flange 20 formed preferably by the punching up of the metal from the flat section 19. The remaining portion of the bracket consists of a shank 21 projecting 80 downward within the mug and formed with guides 22 shown in this instance as being formed of ears bent over adjacent to the inner face of the shank.

While I have referred herein to the making of this device of metal I wish it to be understood that celluloid or any other suitable substantially rigid material might be used in view of the fact that such devices require frequent sterilization. Hence I do 90 not wish to be limited as to any specific variety of material which may be used.

Fixed to the tray 13 by any suitable means is a plunger 23, the main portion of which is vertical and straight and guided within the 95 guides 22. As shown the plunger is bent into a horizontal foot 24 upon which the tray is supported directly and secured by soldering or by rivets 24'. The upper end of the plunger is bent outward at 25 forming 100 a thumb piece directly above and parallel to the flat section 19 of the bracket.

This thumb piece is formed with a lug or flange 26 similar to the lug 20 and directed toward it. The coil spring 27 is interposed between the parts 19 and 25 and held in place by the lugs 20 and 26 which the ends of the spring embrace. This is an expansion spring and tends to lift the plunger and the tray carried thereby holding the foot portion 24 against the lowermost guides 22 as positive stops.

The operation of the attachment is as follows: With a bar or mass of soap S supported upon the tray 13 in the position shown in Fig. 1 when the mug is to be used, 15 the water either hot or cold is delivered into it and partially filling the mug to any desired point somewhat below the bottom of the tray. To form lather the operator simply grasps the mug in the usual manner 20 at the handle and while so grasping the mug will depress the plunger and soap carrier by action of his thumb downward upon the thumb piece 25 against the force of the spring. Thus the tray and soap will be 25 plunged beneath the surface of the water as indicated in dotted lines and thereby the operator may moisten his brush and proceed in the usual manner to form the lather which will be done on top of the soap and 30 preferably after the soap is returned to its normal position, subject however to further moistening if necessary by a subsequent depression of the plunger. The water is always available for this purpose, but is never 35 objectionable because of the tendency of the soap to lie in or below the surface of the water as is commonly the case. After the shaving operation is completed obviously the water may be poured from the mug and 40 the device sterilized if desired. It will thus

be seen that I provide a device of simple and efficient construction and one which serves to insure greatest economy in soap and convenience in operation.

I claim:

1. The herein described soap holder comprising a bracket having means for engagement over the rim of the mug while the bracket projects downward within the mug, a soap tray guided slidably along the bracket, and a spring acting between the bracket and the soap carrier tending to hold the soap carrier elevated.

2. The combination with a mug for a quantity of water, of a soap holder comprising a bracket supported by the rim of the mug and extending thence downward toward the water, a soap carrier movable downward along the bracket, said carrier including a tray and a plunger, said plunger having its upper end bent at an angle to the main portion thereof, and a spring interposed between the bracket and said bent end serving to hold the plunger and tray elevated to permit the plunging thereof downward beneath the surface of the water, substantially as set forth.

3. The herein described soap holder comprising a soap tray, a plunger to which the tray is fixed and extending upward from the tray, a bracket coöperating with the plunger, means to hold the bracket in fixed position, guide means between the plunger and the bracket, means to lift the tray and plunger causing the plunger to be guided along said guide means, and means at the upper end of the plunger to depress the same, substantially as set forth.

FRANCESCO MARTUCCI.
